UNITED STATES PATENT OFFICE.

RAY L. STANCLIFF, OF WESLEYVILLE, PENNSYLVANIA, ASSIGNOR TO GENERAL ELECTRIC COMPANY, A CORPORATION OF NEW YORK.

CONTACT-CONNECTER SHUNT.

Application filed April 4, 1927. Serial No. 180,745.

This invention relates to connector shunts for electrical contacts, such as the contact fingers of drum controllers, electromagnetic contactors or the like where both flexibility and heavy current carrying capacity of the connector shunts are essential to satisfactory operation.

To meet these conditions it has been customary to form the connector shunts for the contacts of a plurality of superimposed, thin, flexible copper strips or laminations which jointly serve to provide the required flexibility and current carrying capacity. Moreover, to facilitate handling the laminated connector shunt as well as the connection of the end thereof to the switch element carrying the contacts, it has been proposed to secure the free ends of the connector laminations into a more or less solid bundle by soldering them together. This, however, is an added, and relatively expensive and difficult operation in manufacturing the connectors. Furthermore, the flux necessarily used in soldering enters between the laminations and starts corrosion which may finally destroy the inner laminations or at least materially shorten the effective life of the laminated connector shunt.

The present invention provides an improved laminated connector shunt for contacts so constructed that the required flexibility and current carrying capacity readily may be obtained and at the same time the superimposed laminations of the connector inherently are bound together at one end of the shunt without the necessity of soldering. Briefly, this is accomplished by making the laminations for the connector shunt substantially double the required length and then folding the laminations over at the middle. This results in the laminations forming a smooth end that does not require soldering and can not be injured by handling. In addition the folded laminations of the connector shunt preferably are crimped or looped up intermediate the ends of the shunt, thereby more effectively insuring the alignment of the laminations and also increasing the flexibility of the shunt.

The single figure of the accompanying drawing is a perspective view of a contact finger provided with a connector shunt, embodying the improvements of the present invention.

As shown in the drawing, the contact fin-

ger 10 is of the type adapted for use in a drum controller and is mounted upon a resilient spring supporting member 11 which in turn is to be secured to the switch element upon which the contact finger 10 is to be used. In accordance with the usual practice the spring support 11 of the contact finger 10 is relieved of the duty of carrying current and the flexible connector shunt 12 is provided for conducting the current to the contact finger 10.

In accordance with the present invention, the connector shunt 12 is formed of a plurality of thin copper strips or laminations 13, as indicated in the drawing. Each of the strips 13 are substantially twice the length of the completed shunt and are folded over at the middle so that the folded-over middle portions of the inner laminations nest within the outer laminations to form the end of the shunt. In this way the outer strip or lamination effectively encircles and binds together all of the inner laminations at the end of the shunt. The laminations are then crimped or looped up as at 14 in order to increase the flexibility of the connector and also more effectively maintain the laminations in alignment.

Thus with the ends of the folded laminations of the conductor secured between the contact 10 and the mounting spring 11 by rivets 15, as shown in the drawing, the connector is maintained definitely in its proper position, thereby facilitating manufacturing, handling and installation of the contact finger unit in a drum controller or other switch mechanism.

What I claim as new and desire to secure by Letters Patent of the United States, is:

1. An electric connector shunt formed of superimposed laminations folded over in the middle with the folded-over middle portions of the inner laminations nesting within the outer laminations to form the end of the shunt.

2. An electric connector shunt formed of superimposed laminations folded over in the middle so that the outer lamination encircles and binds together the folded-over portions of the inner laminations at one end of the shunt, said folded-over laminations being crimped intermediate the ends of the shunt.

3. The combination with a contact finger and a resilient supporting member therefor,

of a connector shunt for the finger formed of superimposed laminations folded over at the middle so that the folded-over middle portions of the laminations nest together at one end of the shunt with the ends of the laminations secured between the finger and the support.

4. The combination with a contact finger and a resilient supporting member therefor, 10 of a connector shunt for the finger formed

of superimposed laminations folded over at the middle so that the folded-over middle portions of the laminations nest together to form one end of the shunt with the ends of the laminations secured between the finger and the support and with the laminations crimped intermediate the ends of the shunt. 15

In witness whereof, I have hereunto set my hand this 1st day of April, 1927.

RAY L. STANCLIFF.
